HEAT EXCHANGE APPARATUS

Charles S. Martel, Medford, Mass., assignor to Standard-Thomson Corporation, Boston, Mass., a corporation of Delaware

Application May 18, 1949, Serial No. 93,917

6 Claims. (Cl. 257—240)

1

The present invention relates to heat exchange apparatus and more particularly to liquid-to-liquid heat exchange apparatus particularly useful for heat transfer between lubricating oil and liquid fuel in turbo-jet aircraft.

The character and quantity of the fuel used in jet propelled aircraft are such as to provide sufficient heat transfer capacity for cooling the oil. This avoids the necessity of an air-to-liquid oil cooler or at least enables the use of a small size of such equipment whereby the aerodynamic difficulties due to introduction of air at high speed may be eliminated or reduced. However the high pressures in both the fuel and oil lines militate against the use of standard forms of heat exchange apparatus.

The object of the present invention is to provide a simple and readily constructed oil cooler capable of efficient heat transfer between liquid and liquid and capable of withstanding high pressures.

To this end the principal feature of the present invention comprises a cellular construction in which the casing is of small cells, each constituting a single path for the oil whereby the use of longitudinal baffle plates is avoided. Each cell is provided with a core of a relatively small bundle of tubes, the tubes being arranged longitudinally in each cell and in a proper association with the parts of the cell to provide for passage of the fuel through the tubes.

In the preferred form the fuel is conveyed through the interior of the tubes and the lubricating oil is circulated outside. The tubes and the casing are constructed to withstand the high pressures in both the fuel and the oil systems. In its preferred form the cells are of extruded aluminum and the tubes are likewise of aluminum whereby the advantages of ruggedness and light weight typified by the Woods Patent No. 2,298,996 are obtained.

Other features of construction consist of certain novel features of construction and combinations and arrangement of parts hereinafter described and particularly defined in the claims.

In the accompanying drawings Fig. 1 is an end elevation of the preferred form of a heat exchange apparatus according to the present invention; Fig. 2 is a side elevation; Fig. 3 is a section on line 3—3 of Fig. 1 showing the flows of oil and cooling fluid; Fig. 4 is a perspective view showing the extruded sections of the shell; Fig. 5 is an elevation of a tube bundle or core; Fig. 6 is an end elevation of the core shown in Fig. 5; Fig. 7 is a detail view showing the core

2

baffles; Fig. 8 is a detail view of the cap for closing the cell; and Figs. 9 and 10 are detail views of end fittings; and Fig. 11 is a section of a modified form of heat exchange apparatus.

3 The heat exchange apparatus shown in Figs. 1 to 4 comprises a casing or shell 10 having a series of connected small cells each indicated at 12. The casing is preferably made of extruded aluminum. In view of the difficulty of extruding 10 the entire cooler in one piece, the extrusion is preferably carried out in sections whereby the two end portions indicated generally at 14 and 16 are each extruded with three cells, while the center section 18 has four cells. The sections 15 are formed with welding flanges 19 (Fig. 4) which are welded together as indicated at 20 (Fig. 1) to form the complete casing. As clearly shown in the drawing, each cell is formed with bowed or arcuate outer side walls to withstand internal pressures.

Received within each cell is a tube bundle indicated at 22. The bundle forms a core of a relatively small number of tubes. For example, in a construction now in use each core has 33 tubes 25 and the dimensions of the cell are approximately 1½ inches across by 2 inches from side to side.

Each core comprises two tube sheets 24, the tubes 6, and the intermediate baffles 28 to be referred to later. The tubes are of extruded aluminum, preferably about ¼ inch in outside diameter and having a wall thickness somewhat greater than is used in liquid-to-air heat exchangers; preferably the wall thickness is about 0.014 inch. The tube sheets 24 are flat aluminum plates properly punched to receive the tubes. The intermediate baffles 28 are arranged to give a sinuous flow to the oil. Hence each baffle comprises a punched section 29 to receive somewhat more than half the tubes and an open section 30 through which the oil may pass in the manner indicated in Fig. 3. Two baffles 28 may be used for each bundle, the two baffles being reversed relatively to each other, whereby the circulating oil is forced from one side of the bundle to the other in a sinuous fashion, so that it contacts all of the tubes without channeling.

A core 22 is inserted into each cell, the tube sheets being of the proper shape to conform closely to the walls of their own cells and the core is positioned therein as shown in Fig. 3. Each core is retained in its corresponding cell by brazing as indicated at 32, the brazing preferably being carried out according to the process described in the Woods Patent No. 2,389,175, dated November 20, 1945.

Immediately inside the tube sheets the cells are provided with ports 33 communicating with adjacent cells for passage of the oil from cell to cell. The oil is introduced in one end cell at 34 and flows in series through the cells to the outlet 35 in the cell at the opposite end.

Immediately beyond the tube sheets 24 are ports 37 for passage of the heat exchange medium through the tubes and cells. An inlet fitting 40 spans the two cells shown in the upper right portion of Fig. 3, and an outlet fitting 42 spans the two cells shown in the lower left corner of Fig. 3. These fittings are brazed or welded to the casing. The cells may be closed by suitable flanges attached to opposite sides of the heat exchange apparatus, but preferably the cells are individually closed by caps 44 shown in Figs. 3 and 8. Each cap is inserted into the end of its corresponding cell and is suitably brazed or welded into position. If desired the caps may be welded to the cells and this construction is preferable because of the greater resistance to pressure.

In operation, fuel serving as the heat exchange medium is introduced at 40 and removed at 42. The fuel may pass through the tubes of the several cores in succession, but to reduce the pressure requirements, the flow is preferably through a series of parallel pairs of cores. Thus, as shown in Fig. 3 the fuel entering at 40 flows through two tube bundles in parallel and is then directed into the next two bundles, and so on, until the last two bundles discharge it into the outlet 42. The ports 37 are disposed so as to provide for parallel flow through adjacent bundles.

A thermostatic oil flow control valve 45 is secured to a pad 46 welded on the casing adjacent the oil outlet 35. The valve is provided with an oil inlet 48 and an outlet 50. A connection 51 runs from the valve body to the oil inlet opening 34. The oil flow is controlled by a thermostatic device shown in outline at 52 in Fig. 2, the construction of which may be of any suitable form familiar to those skilled in the art whereby the oil may be directed from the valve inlet 48 through 52 to the casing inlet 34 and thence around the tubes to the outlet 50, as indicated by the solid arrows in Fig. 2, or may be by-passed from 48 to 50 as indicated by the broken arrow. When the oil is hot, it is circulated through the exchanger, but when its temperature falls below a certain point, it is by-passed from the cooler.

It will be observed that the general flows of liquids are counter-current.

An important feature of the invention is the arrangement to withstand high pressures. The pressures are relatively high, in some instances being about 1,000 pounds per square inch for the fuel and about 300 pounds per square inch for the oil. The tubes have a sufficient wall thickness to withstand the internal pressure. Furthermore, the system is highly resistant to oil surges without the necessity of using a surge-relief valve as is customary in heat exchangers of the conventional type. The small cellular construction resists bursting pressures of the casing up to any surge pressures normally encountered. Furthermore, the surges do not affect the tubes since no crushing pressure is applied to the tubes until the external pressure exceeds the internal pressure. Since surges of more than 1,000 pounds per square inch are not usually encountered, there is no tendency toward crushing of the tubes. The avoidance of the

surge-relief valve is important for reasons of reduced cost and improved reliability.

The arcuate arrangement of Fig. 1 is useful in some designs where the heat exchanger partly surrounds the jet engine or other equipment. Where such an arrangement is not required the cells may be arranged in a straight pattern, either in a single row or in a plurality of rows, as indicated in Fig. 11, wherein an extruded casing 54 is formed with small cells 56 having pressure-resisting curved outer walls 58, and internal partitions, shown as straight longitudinal walls 60 and transverse walls 62. The tube bundles or cores may be mounted as shown at 64. No flow diagrams are given in Fig. 11, and the particular arrangements of the parts, fittings, closures, etc. are not shown, since they will, in general, be similar to those previously described.

Although the invention has been described as embodied in an oil-to-fuel heat exchanger for aircraft, it is not limited to such service but may be applied to any liquid-to-liquid exchanger, especially for operation at high pressures.

Having thus described my invention, I claim:

1. A liquid-to-liquid heat exchanger for operation at high liquid pressures comprising an extruded shell having a plurality of small tubular cells, each cell having a generally cylindrical exterior surface, the shell having unitary partitions separating adjacent cells, a core for each cell comprising a bundle of straight tubes, each core having tube sheets at opposite ends, each tube sheet being of the same shape as the cross-section of its corresponding shell, means for sealing the tube sheets into the cells, inlet and outlet members connected to direct one liquid through the tubes, the partitions having ports outside the tube sheets on opposite sides to direct said liquid through the tubes and having ports between the tube sheets on opposite sides of adjacent cells to direct the other liquid in a series of longitudinal passes around the tubes in the several cells, and closures for the ends of the cells.

2. A liquid-to-liquid heat exchanger for operation at high liquid pressures comprising an extruded shell having a plurality of small tubular cells, each cell having a generally cylindrical exterior surface, the shell having unitary partitions separating adjacent cells, a core for each cell comprising a bundle of straight tubes, each core having tube sheets at opposite ends, each tube sheet being of the same shape as the cross-section of its corresponding shell, means for sealing the tube sheets into the cells, inlet and outlet members connected to direct one liquid through the tubes, the partitions having ports outside the tube sheets on opposite sides to direct said liquid through the tubes and having ports between the tube sheets on opposite sides of adjacent cells to direct the other liquid in a series of longitudinal passes around the tubes in the several cells, baffle members mounted on each bundle and having open portions extending partially across the tube space to impart a sinuous path to said other liquid, and closures for the ends of the cells.

3. A liquid-to-liquid heat exchanger for operation at high liquid pressures comprising an extruded shell having a plurality of small tubular cells, each cell having a generally cylindrical exterior surface, the shell having unitary partitions separating adjacent cells, a core for each cell comprising a bundle of straight tubes, each core having tube sheets at opposite ends, each tube

sheet being of the same shape as the cross-section of its corresponding shell, means for sealing the tube sheets into the cells, inlet and outlet members connected to direct one liquid through the tubes, the partitions having ports outside the tube sheets on opposite sides to direct said liquid through the tubes and having ports between the tube sheets on opposite sides of adjacent cells to direct the other liquid in a series of longitudinal passes around the tubes in the several cells, and individual closures welded into the cells at the ends thereof.

4. A heat exchanger as defined in claim 1 wherein the cells are arranged in a single arcuate row on an arc of large radius.

5. A heat exchanger as defined in claim 1 having a plurality of extruded sections each section having a plurality of cells and provided with a welding flange, the sections being welded together.

6. A heat exchanger as defined in claim 1 in which the several cells are arranged in a plu-

rality of rows with longitudinal and transverse internal dividing walls.
